UNITED STATES PATENT OFFICE.

WILLIAM M. FLETCHER, OF BINGHAMTON, NEW YORK.

HORSESHOE.

1,027,410.

Specification of Letters Patent.

Patented May 28, 1912.

Application filed August 2, 1911. Serial No. 641,948.

To all whom it may concern:

Be it known that I, WILLIAM M. FLETCHER, a citizen of the United States, residing at Binghamton, in the county of Broome and State of New York, have invented a certain new and useful Improvement in Horse-shoes, of which the following is a full, clear, concise, and exact description, reference being had to the accompanying drawings, which form a part of this specification.

My invention relates to that class of horse-shoes which are provided with detachable calks having shanks which fit into apertures in the shoe proper.

In horseshoes of this class it has been customary heretofore to have the parts which secure the calks to the shoe project and I have found in practice that such projecting parts are apt to be broken when the horse is tramping over rough pavements, or else bent so as to make it difficult to remove and replace the calks when these are worn out.

The object of my invention is to overcome this difficulty by so constructing the members which hold the calks in place that these members shall not project beyond the shoe, and by providing guards for protecting and partly inclosing the means which keep the said members from slipping out of their normal places.

Reference is to be had to the accompanying drawings forming part of this specification, in which—

Figure 1 is a bottom view of a horseshoe constructed in accordance with my invention; Fig. 2 is a sectional view taken on the line 2—2 of Fig. 1, and looking in the direction indicated by the arrow; Fig. 3 is an elevation looking from the toe of the shoe, and Fig. 4 is a detail sectional view showing a modified form of heel calk.

In the drawings, the body A of the horse-shoe is provided with suitably arranged vertical holes B B' for receiving the shanks C C' of the calks D D', these shanks and the holes for the same being preferably oblong in section. The shoe is also provided with horizontal holes E E' passing through the walls of the shoe on opposite sides of each of the vertical holes B B', these horizontal holes being preferably round in section and of uniform diameter. I also provide holes F F' in each calk, these holes corresponding in diameter to the holes E E' in the shoe and being so placed as to aline or

register with the holes E E' when the calks are slipped into their normal places. Tubular fastening pins G G' are slipped through these alined holes E F E and E' F' E', 60 these pins being preferably of steel and not long enough to project beyond the edge of the shoe at each end. Through the bore of these pins G G' I slip retaining members, these being preferably wires H H' running 65 in grooves I I' around the adjacent parts of the shoe. The ends of each such retaining member may be joined in any suitable manner, or they may be left unjoined as shown in the drawings in which the two ends approach close to each other within the bore 70 of the tubular pin.

It will readily be seen that by my construction the retaining members H H' are 75 protected against mechanical injury by being run in the grooves and that the tubular fastening pins themselves are entirely inclosed within the shoe and calk, thereby protecting them from injury. When it is desired to replace the calk, the wires H H' 80 can easily be pried out with any sharp tool, thereby releasing the pins G G' which can then be driven out with a nail.

For heel calks I have found a single such fastening pin to be sufficient, but for toe 85 calks it may be advisable to use two pins through the single calk as shown in Fig. 1.

Having thus described my invention, what I claim as new and desire to cover by Letters Patent is:—

1. A horseshoe including a shoe body provided with a vertical perforation and with horizontal perforations opening into the vertical perforation; a calk having a shank to fit the vertical perforation, said shank having a perforation alining with the horizontal perforations when the shank is positioned in the aforesaid vertical perforation; a tubular pin passing through the alined openings in the shank stem and shoe body; 100 and a retaining member passing through the tubular pin and around an adjoining part of the shoe body to hold the said tubular pin in place.

2. A horseshoe including a shoe body provided with a vertical perforation and with horizontal perforations opening into the vertical perforation; a calk having a shank to fit the vertical perforation, said shank having a perforation alining with the horizontal perforations when the shank is positioned in the aforesaid vertical perforation;

a tubular pin passing through the alined openings in the shank stem and shoe body; and a retaining member passing through the tubular pin and around an adjoining part of 5 the shoe body to hold the said tubular pin in place, there being grooves in the shoe body to receive the retaining member so as to protect it from injury.

In witness whereof, I have hereunto set my hand, this 18th day of July A. D. 1911, 10 in the presence of two subscribing witnesses.

WILLIAM M. FLETCHER.
